UNITED STATES PATENT OFFICE.

HENRY H. CAMPBELL, OF CLEVELAND, OHIO.

INCLINED GRATE FOR AUTOMATIC STOKING.

SPECIFICATION forming part of Letters Patent No. 702,538, dated June 17, 1902.

Application filed July 6, 1896. Serial No. 598,113. (No model.)

To all whom it may concern:

Be it known that I, HENRY H. CAMPBELL, a citizen of the United States, residing at Cleveland, in the county of Cuyahoga and State of Ohio, have invented certain new and useful Improvements in Inclined Grates for Automatic Stoking; and I do hereby declare that the following is a full, clear, and exact description of the invention, which will enable others skilled in the art to which it appertains to make and use the same.

My invention relates to inclined grates for automatic stoking, and the invention is an improvement in a style of grate known now as "The Brightman" and first disclosed in United States Patent No. 318,862, May 26, 1885, and subsequently improved by H. H. Campbell and patented September 26, 1893, No. 505,748. The present improvement is supplemental to the said Campbell patent, and embodies an improvement which time and experience with this particular stoker or grate have shown to be necessary in order that satisfactory results may be obtained.

The particular defect remedied by the present invention is the defective feed which was encountered over the longitudinal bars which support the fuel-carrying shelves; and the invention therefore consists in a stoker having a feed-grate constructed and operating substantially as shown and described, and particularly pointed out in the claim.

In the accompanying drawings, Figure 1 is a vertical sectional elevation of a grate embodying my invention; and Fig. 2 is a perspective view of a portion of the said grate, as hereinafter more fully described.

A represents the inclined side pieces or bars constituting the stationary portions of the said grate and having lateral and horizontally-disposed shelves 2 integral therewith, and B represents the corresponding side pieces or bars of the reciprocating portion of the grate and having shelves 3 integral therewith at their sides. These bars A and B, with their shelves 2 and 3, are supported as heretofore or in an equivalent way, the means of support not forming a part of this invention.

It will be noticed that the bars A and B are arranged in pairs side by side, while their shelves 2 and 3 project from opposite sides, but on the same plane in each set—that is,

the shelves 2 of the bars A are on the same plane all the way across the furnace, and the shelves 3 in their series extend all the way across the furnace also; but the said shelves alternate from top to bottom of the grate, there being first, say, a series of the shelves or steps 3 and then a series of shelves 2, and so on successively. It will be further noticed that while the shelves alternate in this way they also overlap one another, so that 2 overlaps 3 and 3 overlaps 2, and that a uniform space intervenes between the successive shelves. The shelves 2 project laterally to the next bar B on one side, while the shelves 3 project laterally to the next bar A on the other side; but the shelves have to do only with the bars of which they form a part, and thus we have successive and alternate stationary and reciprocating grates A² and B³, respectively. This brings us to the consideration of the point of departure in this invention from that which has gone before and is disclosed in the patents above mentioned. Thus in said patents the shelves corresponding to 2 and 3 in this case were located so as to bring their front edge flush with the inclined top or front edge, (indicated by 4 in these drawings.) This served a fairly good purpose; but in time I discovered that the construction was defective, because there was nothing to break up the coal, which baked and packed immediately over and upon the said edges 4 of the bars A and B. The consequence was that while the reciprocation of grate members B was sufficient for all purposes, so far as the space between the several grate-bars A and B was concerned, it was wholly inadequate and deficient so far as the space over said bars was concerned. Hence I found it necessary to remedy this defect and have done so by constructing the shelves 2 and 3 as shown. In this construction it will be seen that the said shelves all project a considerable distance out beyond the said edges 4 as seen at 5 and 6, respectively, and this works the desired remedy. Thus at 5 on each of the bars A and at 6 on each of the bars B the said shelves are built out over their bars, as shown, thus throwing a shoulder or projection across the otherwise plain edge of said bars, while at the opposite edges the said shelves project out at the immediate sides of the bars A and B.

B and serve to break up the coal at those points which come between the shoulders 5 or 6, as the case may be. Both shelves 2 and 3 have these advanced edges alike, and their effect is substantially the same in each case when the grate is operated to move the coal.

The grate-bars B are supported at their lower ends on the rocker 8 and at their upper ends on the standard 9 and have a substantially horizontal movement—that is, the movement is inward and outward in about a horizontal plane, so far as the shelves 3 are concerned. This moves every alternate shelf and leaves the other alternate shelves 2 standing in stationary position. In that case the corners 7 of shelves 3 serve to break up the coal in the edges of bar A, while the corners 7 of the shelves 2 serve to break up the coal along the edge of bars B. Furthermore, as the coal works down over the edges 4 of the bars A and B it must ride over the projections 5 and 6, which will help to break it up and open it up to draft from between and about said bars.

What I claim as new, and desire to secure 25 by Letters Patent, is—

In furnace-grates, a set of fixed grate-bars A arranged in pairs and a set of movable grate-bars B arranged in pairs and alternating with the said fixed bars, both said bars A 30 and B having horizontal shelves which extend laterally to the next adjoining bar on each side, the shelves of the movable bars interlocking with those of the fixed bars, and the shelves of all the bars extending out beyond the upper surface of the bars and forming projections thereon, all the bars being supported in an inclined position, and means to impart movement to the movable bars in a substantially horizontal direction, substantially as described.

Witness my hand to the foregoing specification on this 3d day of June, 1896.

HENRY H. CAMPBELL.
